UNITED STATES PATENT OFFICE.

WALTER CLAUDE JOHNSON, OF COLEMANS HATCH, ENGLAND.

WATER-DISTRIBUTER.

No. 902,662.

Specification of Letters Patent.

Patented Nov. 3, 1908.

Application filed December 4, 1907. Serial No. 405,008.

To all whom it may concern:

Be it known that I, WALTER CLAUDE JOHNSON, subject of the King of Great Britain, residing at Broadstone Farm, Colemans Hatch, Sussex, England, have invented a new and useful Improved Water-Distributer, of which the following is a specification.

This invention relates to an improved method whereby water may automatically be uniformly distributed over a relatively large area or surface, and the means whereby this kind of distribution may be effectually accomplished, the purpose of the invention being to effect watering or fire-extinguishing.

The method consists in projecting water at high velocity through a nozzle which is so mounted as to be adapted to undergo a gradual angular deviation, alternately from and towards a vertical line, while the plane of angular movement of the axis of the nozzle rotates continuously about a vertical axis at the center of the area of distribution. On the ratio adopted of the period occupied by the swing to that of the rotation, will depend the form of the path wetted by the continuous stream of water. That which will effect the gradual covering of the entire area or surface to be watered, in a manner involving the least movement of the parts of the machine will be such that the wetted path is a spiral of gradually increasing, alternated with gradually diminishing radius, in which case the period of the swing will be considerable, relatively to the period occupied by the rotation. In the examples shown on the accompanying drawings such a periodic ratio has been adopted.

The desired change of position and direction of the nozzle is effected by a portion of the energy of the water supplied for distribution, operated by a small vane-carrying wheel through the medium of spur-wheels and a worm and worm-wheel.

The accompanying drawings show two constructional modifications.

In these drawings:—Figures 1-3 are a vertical section, a plan and a part end elevation respectively of one form of construction. Fig. 4 is a diagram showing the spiral path which is watered, and Fig. 5 is a vertical section of a modified form of construction which is adapted to water areas which have a non-circular boundary line.

Referring first to Figs. 1-3, the water is conducted under pressure to the distributer

through a hose which is connected to the admission pipe *a* from which it flows through a turbine wheel *b* formed with inclined vanes. Before reaching the wheel *b*, the water passes between inclined guide-blades *a*¹ formed within the admission pipe *a* which guide-blades give a twist to the water flowing between them, the twist being utilized in driving the wheel, and taken out of the water by the re-action thereof, so that the further progress of the water is with little or no whirl. On leaving the wheel *b* the water enters a casing *c* in which the spindle *b*¹ of the wheel *b* is mounted and from *c* the water flows through a vertical pipe *d* rotatably mounted within a bush *e* which passes through a central aperture in the base plate *f*. The bush *e* being screwed tightly into the casing *c* will serve to fasten *c* and *e* to the base plate *f* and provide a vertical bearing for the pipe *d*. To the upper end of the vertical pipe *d* is secured an elbow *g* directed radially, and projecting from this is an extension *h* which carries, pivotally mounted thereon, the socket *i* of an upward projecting converging nozzle *j* through which the issuing stream of water is directed.

The motive power for deviating the path of the projected stream is derived from the wheel *b* by means of the rotating spindle *b*¹ which emerges through the casing *c* and has secured to its extremity a worm *k* which gears with a worm-wheel *m* keyed to a spindle *n* which is mounted in a bearing provided in the base *f*. To the upper end of the spindle *n* is keyed a pinion *o* which gears simultaneously with two spur-wheels *p* and *q* one of which has one or more teeth in excess of the other. The wheel *p* is secured to the before mentioned vertical pipe *d*, which thereby is caused to rotate. The other wheel *q* carries a roller-face *r* whereby the angle of elevation of the axis of the nozzle undergoes a gradual change, causing the projected stream of water to drop onto the surface of the ground in a spiral path the radius of which gradually increases up to a limit and then gradually diminishes to a minimum, and so on successively.

The gradual change of the angle of elevation of the nozzle is derived from its slow angular displacement relatively to the race *r*, which is due to the difference in the number of teeth in the wheels *p* and *q*. The mechanism for varying the angle of elevation of the nozzle is constructed as follows:—

Formed in one with the before mentioned elbow g is a bearing for a horizontal spindle s to which, at one end, is secured a lever arm t carrying a roller t^1 which traverses the race r and, at the other end, a lever-arm u connected by a link v to the delivery nozzle j . On the spindle s is a spring w so strained as to press the roller t^1 on to the race r . The vertical contour of the race r is such as to cause the angle of elevation of the axis of the nozzle to diminish from being exactly or approximately a right-angle, to such a degree as would effect the desired range of distribution of the stream of water and subsequently cause a gradual increase of the angle and so on repeatedly. The radial distance from the center of rotation of the roller t^1 is made adjustable by means of the pinching screw t^2 and thereby the area of the ground watered can be regulated as desired. The time occupied by a rotation of the nozzle around the central vertical axis of the machine will be normally the same at all angles of elevation. Accordingly in order to compensate for the greater length of surface over which the water is distributed as the radius increases, the roller race is so shaped that the increment per revolution of the radius of the spiral gradually diminishes as shown in Fig. 4.

Fig. 5 shows a modification of the construction. In this a device is added whereby, in addition to the regular and gradual tilting of the nozzle effected by the race r , a secondary tilting action is superposed. By this means the contrivance can be adapted to water a non-circular area, such as a rectangular grass-plot for example. The secondary tilting device comprises a cam-plate x , the plan of which is an annular ring having four elevated portions situated on radial lines which lie in the directions of the sides of the rectangular area to be watered, there being depressions between the elevations the lowest portion of which are situated on radial lines directed towards the corners of the rectangle, the elevations in the direction of the shorter side being higher than the two intermediate elevations. A loose pin y mounted in the before mentioned wheel p rides on this cam-plate x and by pressing upwards beneath the wheel q alternatively raises and lowers the race r increasing the angle of elevation of the nozzle when raised and diminishing the range of the jet.

The contrivance above described is adapt-

ed not only to distribute water over an open area for cooling or cultivation purposes, but it can also be employed as a fire extinguisher whereby the water will automatically be directed so as to impinge in turn over every portion of the ceiling, walls and floor of a surrounding building, or alternatively the water distributor may be affixed in an inverted manner to the center of the ceiling of a large room. When used for fire extinguishing it will be desirable that it be automatically started into action by some agent which under the influence of an abrupt rise of temperature would be set into operation.

I claim.

1. In a water distributor, a nozzle, means for automatically effecting a gradual variation of the angle of elevation of said nozzle, means for automatically rotating the plane of elevation of said nozzle and means for periodically modifying during each revolution the action of said means for varying the angle of elevation.

2. In a water distributor, a stand, a water supply pipe attached thereto, a pivoted nozzle rotatably mounted on said stand and communicating with said pipe, a vaned wheel located between said pipe and said nozzle, a spur-wheel connected with said nozzle, a second spur-wheel having a different number of teeth from said nozzle spur wheel, gearing connecting said vaned wheel with said spur wheels, a race on said second spur wheel and a roller connected with said nozzle and bearing on said race.

3. In a water distributor, a stand, a water supply pipe attached thereto, a pivoted nozzle rotatably mounted on said stand and communicating with said pipe, a vaned wheel located between said pipe and said nozzle, a spur-wheel connected with said nozzle, a second spur wheel having a different number of teeth from said nozzle spur wheel, gearing connecting said vaned wheel with said spur wheels, a race on said second spur wheel, a roller connected with said nozzle and bearing on said race, a fixed cam-plate on said stand and a pin loosely mounted in said nozzle spur wheel and bearing on said race wheel and cam-plate respectively.

In witness whereof I have hereunto set my hand in presence of two witnesses.

W. CLAUDE JOHNSON.
